UNITED STATES PATENT OFFICE.

MORGAN LAVERING AND JACOB SCHWAB, JR., OF DENVER, COLORADO.

RAIL-JOINT.

1,147,518.

Specification of Letters Patent. Patented July 20, 1915.

Application filed August 11, 1914. Serial No. 856,195.

To all whom it may concern:

Be it known that we, MORGAN LAVERING and JACOB SCHWAB, JR., citizens of the United States, residing at Denver, in the county of Denver and State of Colorado, have invented new and useful Improvements in Rail-Joints, of which the following is a specification.

This invention relates to improvements in means for connecting the ends of railway rails, and one of the objects of the invention is to provide interengaging members for the heads of the rails which will materially assist the fish plates in sustaining the heads of the rails against vertical movement.

With the above and other objects in view, the improvement resides in the construction, combination and arrangement of parts set forth in the following specification and falling within the scope of the appended claim.

In the drawings: Figure 1 is a perspective view illustrating two rails connected in accordance with our improvement, Fig. 2 is a similar view with one of the fish plates removed, Fig. 3 is a top plan view of the jointed rails, Fig. 4 is a transverse section approximately on the line 4—4 of Fig. 2, Fig. 5 is a detail horizontal section approximately on the line 5—5 of Fig. 1, and Fig. 6 is a perspective view of the rail ends, the same being separated.

The rails 1—1' have their body portions of the usual construction, but their ends are beveled in opposite directions, as indicated by the numerals 2—2', each of the beveled faces terminating in a shoulder 3 at the head upon the beveled side of the rail, and also terminating in a shoulder at the end of the head. The beveled wall extends from the shoulder 3 entirely through the web of each of the rails, while the outer ends of the base flanges of the rails provide shoulders 5.

The head of each of the rails, adjacent the end of the said head is provided with an opening 15 and the outer beveled wall of each of said heads is formed with a socket 14. The sockets 14 are adapted to aline or

register with the openings 15 when the rail ends are assembled. Arranged within each of said sockets 14 is a sleeve 12, the said sleeves projecting beyond the beveled faces of the rails a distance approximately equaling the length of the openings 15, and the said sleeves are adapted to be received within the respective openings 15. These sleeves 12 are preferably constructed of some electric conducting material such as copper, and in order to sustain the said sleeves in their respective sockets, we provide metal pins 13 which we force in the bore of the sleeves to expand the same to force them into tight engagement with the walls provided by the sockets. The side walls of the openings 15 are not, however, contacted by the sleeves 12, so that the longitudinal movement of the rail ends incident to climatic changes is not interfered with.

When the rail ends are assembled the shoulders 3 which are arranged upon the heads of the rails at a distance from the ends of the webs of the rails, contact, each with the shoulders 4 provided upon the outer ends of the heads of the rails while the shoulders 5 upon the extreme ends of the base flanges will contact with the shoulders 6 upon the edges at the beveled portions of the bases. The webs of the rails are provided with a plurality of transverse openings, while fish plates or angle bars 8 are adapted to be received within the fishing spaces of the rails at the end thereof, the same having openings which correspond with the openings in the webs of the rails and being adapted to receive transverse securing bolts 9 provided with locking nuts 10.

Having thus described the invention, what we claim is:

Two railway rails having their opposite faces beveled, the head of each of the rails adjacent its outer end being provided with an opening, the said beveled face of each of the rails having a laterally arranged socket which is adapted to register with the opening in the co-acting rail when the rail ends are assembled, a compressible sleeve within

each of the sockets and projecting therefrom and adapted to be received in the opening of the co-engaging rail, pin members, said pin members adapted to be inserted in the sleeves to expand the said sleeves to cause the same to bind against the walls of the socket and to contact with two of the walls of the openings.

In testimony whereof we affix our signatures in presence of two witnesses.

MORGAN LAVERING.
JACOB SCHWAB, JR.
